UNITED STATES PATENT OFFICE.

ARTHUR J. RAY, OF LIVERPOOL, ENGLAND, ASSIGNOR TO AUTOMATIC ELECTRIC COMPANY, OF CHICAGO, ILLINOIS, A CORPORATION OF ILLINOIS.

TELEPHONE SYSTEM.

1,304,369.

Specification of Letters Patent. Patented May 20, 1919.

Application filed January 26, 1915, Serial No. 4,573. Renewed August 26, 1918. Serial No. 251,541.

To all whom it may concern:

Be it known that I, ARTHUR J. RAY, a citizen of the United States, residing at Liverpool, county of Lancashire, England, have invented a new and useful Improvement in Telephone Systems, of which the following is a specification.

This invention relates to modifications of circuit arrangements for operating subscribers' meters or call registers in telephone systems. The invention is particularly, though not exclusively, applicable to automatic telephone systems in which the subscribers' lines are connected with the first group selectors through the medium of preliminary switching devices, either call finders or trunk selectors. The invention is further applicable to automatic systems in which the direction of current in the calling line is reversed on the response of the called subscriber, and is therefore in the nature of an improvement on the arrangement shown in British Patent No. 1298 of 1910.

It is the object of the invention to reduce the number of wires connecting the meter with the subscriber's individual switch or line equipment in the central office. In accordance with this object, therefore, a relay is allocated to each of the trunk lines to which the calling subscribers have access through the preliminary switching devices, which relays are operated upon the response of the called subscribers and close the circuits of the calling subscribers' meters which are connected up to the contact springs of the relays through extra bank contacts of the preliminary switches, when the switches are operated.

In Figs. 1 and 2 of the accompanying drawings there is shown a complete connection from a calling telephone A to a called telephone A¹ in an automatic telephone system in connection with which it has been chosen to illustrate the invention. On these drawings, the calling lines obtain connection with the first numerical switch through two series of non-numerical switches C and C².

This arrangement is similar to that shown in British Patent No. 1421 of 1910. The trunk lines to which the switches C² have

access are shown leading direct to connector switches E, but it is to be understood that any number of selector switches might be included in the connection preceding the connector.

The substation A (Fig. 1) may be of any suitable or approved type, and, as shown herein, comprises the usual receiver 2, transmitter 3, ringer 4 and condenser 5. Being a so-called automatic substation, it is also provided with an impulse transmitter or calling device, which is herein represented by a pair of impulse springs 6 and 7 and an impulse wheel 8, which latter may be controlled by a finger hold dial or other device to separate the springs 6 and 7 momentarily a number of times for each digit of the number to be called.

The subscriber's individual switch C is of the general type of subscriber's switch shown in British Patent No. 26301 of 1906, more closely resembling, however, the particular type shown in British Patent No. 1421 of 1910. This line switch comprises, among other details, a plunger (not shown) attached to the end of a so-called plunger arm 9, which is controlled by a magnet 10, which comprises an operating winding 11 and a holding winding 12. This magnet also controls the cut-off armature 13. The winding 11 operates both plunger arm 9 and armature 13, while winding 12 is strong enough only to operate the armature 13 and to hold the plunger arm 9 in its operated position. When the plunger arm is attracted, the line connection is extended through a set of springs 14, 15, 16, 17, 18, 19, 20 and 21 to a secondary switch C². A so-called master switch D maintains the plungers of idle switches in position to engage an idle trunk line in a well-known manner.

Each subscriber's line is provided with a call register M, the magnet 22 of which is connected to spring 20 of switch C by a single wire.

Allocated to each of the trunk lines to which the switches C have access are two relays 23 and 24. The relay 24 is so constructed and adjusted that it requires both its windings to be energized in the same

55

direction to attract its armature. The relay 23 has a sufficiently high resistance to prevent the meter magnet 22 energizing in series with it.

5 The secondary switch C^2 is, in general, similar to the primary switch C . The detail differences between these switches will be evident from the description of the operation which is to follow. A group of switches C^2 10 is controlled by a common master switch D^1 which is similar to the master switch D . Since the operation of the invention described herein is not dependent on the operation of the master switches, it is not 15 thought necessary to describe their construction and operation herein. These switches are fully described in the publications hereinabove referred to.

The connector switch E is of the same 20 general type of connector switch as disclosed in United States Letters Patent No. 815176, granted March 13th, 1906, to Keith, Erickson and Erickson, the circuits, however, being modified in a manner similar to that 25 shown in British Patent No. 1421 of 1910 to adapt the switch to operate in a system in which the central office apparatus is controlled by impulses delivered over the two sides of the line in series. The connector is 30 provided with a shaft (not shown) carrying the wipers 25, 26 and 27, which is controlled by the vertical magnet 28 and the rotary magnet 29. The usual side switch comprising the wipers 30, 31, 32 and 33 is 35 controlled by the private magnet 34 in the usual well-known manner. The magnet 34 is the usual release magnet. The line relay 35 is connected with the calling line through the reversing springs of the so-called back bridge relay 36. The ringing relay 37 is the means through which ringing current is applied to the called line.

The called substation A^1 , together with its 40 individual switch C^1 and meter M^1 , are similar in all respects to the substation A , together with its individual switch C and meter M .

A general description of the apparatus having been given, it will now be explained 45 how the connection is extended from the telephone A to the called telephone A^1 , and how the completed call is recorded on the calling subscriber's call register M . It will be assumed that the number of the called 50 line is number 20.

Upon the removal of the receiver from the switch hook at the telephone A , preparatory to making a call the circuit of the line relay 40 is closed from the battery lead 50 through 55 relay 40, springs 41 and 42, thence over the line to and through the telephone A and back over the other side of the line and through the springs 43 and 44 to earth G^2 . The relay 40, upon energizing, closes the circuit 60 of the operating winding 11 which op-

erates to disconnect the relay 40 from the line through the medium of the armature 13, and to thrust the plunger of the switch into the terminal of the junction line before which it is being held by the master switch, 70 whereby the line circuit is extended through the springs 14 and 15 and 16 and 17 to an idle secondary switch C^2 . On the closing of springs 20 and 21 of switch C a circuit is closed from battery lead 50 through relay 23 75 of the selected junction line, springs 21 and 20, and meter magnet 22 to earth G^3 . The current in this circuit is not sufficient to operate the meter magnet 22, but the relay 23 is operated, earthing the master switch bank 80 contact 45 to mark the junction as engaged. The relay 23 also closes a circuit from earth G^4 through springs 46, operating winding 47 of switch C^2 , springs 51 and 52, relay 54 and contacts 55 and 56 to battery lead 50. The winding 47 attracts the plunger arm of the switch to extend the line connection through the springs 57 and 58, 59 and 60, and conductors 61 and 62 to the connector E , and to shift the connection of winding 47 to battery through the high resistance holding winding 63 instead of through relay 54 and contacts 55 and 56. The slow-acting relay 54 is energized only for a short time to provide a holding circuit from earth G^4 for the 90 winding 12 of the switch C till said circuit is earthed at the connector E which is brought about as follows:—When connection is extended to the connector E over the conductors 61 and 62, a circuit is closed extending from earth through the lower winding of the connector line relay 35, a normally closed contact of relay 36, conductor 62, springs 60 and 59, 17 and 16, telephone A, springs 14 and 15, left hand winding of 105 relay 24, springs 57 and 58, conductor 61, a contact of relay 36 and upper winding of relay 35 to battery lead 50. Relay 35, upon energizing, closes the circuit of relay 64 which in turn closes a circuit from earth G^5 110 through the springs 65, conductor 66, relay 67, springs 68 and 69, conductor 70, springs 19 and 18 and holding winding 12 of switch C to battery lead 50. From the spring 18, a connection extends to the connector private 115 bank contacts of the calling line over which said contacts are earthed to mark the line as engaged. From the conductor 70 in the circuit traced above a branch circuit extends through the right hand winding of relay 24 120 to battery lead 50. The current in this winding is opposed at this time by the line current in the other winding and the relay is not operatively energized. When all the junction lines outgoing from a group or 125 board of secondary switches are in use simultaneously, the relays 67 of all these junction lines co-operate to close the circuit of relay 98 which opens the contact 71 to prevent the master switch D' operating contin- 130

uously. During the time the outgoing junctions are all engaged, all the incoming junctions are guarded against seizure by the de-energization of relay 72.

5 The calling subscriber now operates his calling device for the first digit 2 of the called number, whereby the substation impulse springs 6 and 7 are separated twice momentarily, each time breaking the circuit 10 of the connector line relay 35. The relay 64 of the connector switch being slow acting does not de-energize during the momentary interruptions of its circuit by the line relay 35, and consequently, each time the latter relay de-energizes, an impulse is transmitted over the circuit extending from ground G^6 , through the contact of springs 76 and 75, springs 77 and 78 of the relay 64, slow acting relay 79, the vertical magnet 28 15 and the side switch wiper 30 in first position to battery B. The vertical magnet receives two impulses over this circuit and operates to raise the switch shaft and wipers to a position opposite the second level of bank contacts. The relay 79, which was included in 20 series with the vertical magnet, remains in its energized position during the entire time that impulses are being transmitted through it and operates to close the circuit of the private magnet 34. This circuit extends from ground G^7 , through the contact of springs 80 and 81 and the said magnet to battery B. After the last impulse is delivered, the relay 79 opens the circuit of the private 25 magnet 34, which, upon de-energizing, permits the side switch to advance from first to second position in a well-known manner. The movement of the side switch wiper 30 from first to second position transfers the 30 battery connection from the vertical magnet 28 to the rotary magnet 29. The calling subscriber now operates his calling device for the last digit 0, in response to which the connector line relay operates to transmit ten 35 impulses through the rotary magnet 29 in series with the relay 79, whereby the shaft and wipers are rotated on to the contacts of the desired line. The circuit extends from ground G^8 through the contact of springs 40 76 and 75, springs 77 and 78, relay 79, springs 82, the rotary magnet 29 and the side switch wiper 30 in second position to the battery B. If the called line is idle, the private magnet 34 de-energizes when its 45 circuit is broken by the relay 79 after the last impulse is delivered to the rotary magnet 29. The de-energization of the private magnet 34 allows the side switch to advance one more position, that is, from second to third position. By the engagement of the side switch wipers 32 and 33 with their third position contact points the connection is completed with the called substation. The circuit for the bridge cut-off winding of line switch C^1 50 extends from ground G^8 , through the side switch wiper 31 in third position, private wiper 26, conductor 84 and the said cut-off winding to the battery lead 100. The said winding, upon energizing, operates to disconnect the line winding 85 of the line switch 55 C^1 from the line. A guarding ground potential is supplied to the connector private bank contact of the called line, which prevents the called line from being seized by some other connector switch. By the engagement of the side switch wiper 30 with its third position contact point, the circuit of the ringing relay 37 is closed. The circuit extends from ground G^9 , through the interrupter 86, relay 37, springs 87 and the side switch wiper 30 60 in third position to the battery B. The ringing relay, upon energizing, disconnects the called line from the calling and bridges the ringing generator R across the called line. The ringing relay is energized only intermittently through the medium of the interrupter 86. Upon the response of the called subscriber, his line is provided with talking current through the back bridge relay 36. The relay 36, upon energizing, 65 closes the circuit of the ringer cut-off relay 88. This circuit extends from ground G^8 through the side switch wiper 31 in third position, contact of springs 89 and the relay 88 to battery B. The relay 88, upon 70 energizing, interrupts the circuit of the ringer relay 37 at the springs 87 and closes a locking circuit for itself through the springs 90 independent of the springs 89. A further result of the energization of the back bridge relay 36, upon response of the called subscriber, is the transposition of the connection of the windings of the line relay 35 with regard to the line, whereby the direction of the current in the calling line is 75 reversed, and consequently in the left hand winding of the meter controlling relay 24 (Fig. 1). This reversal of current in one of the windings of the relay 24 causes the two windings to assist each other, and the relay 80 is operatively energized. At the contact of springs 91, the relay 24 shunts the relay 23 by the low resistance 93 thereby increasing the current in the meter magnet 22 sufficiently to cause it to operate to register the 85 call. The contact of the springs 94 provides an earth connection for holding the switch C² in case the relay 23 is de-energized when shunted by the resistance 93. On energizing, the relay 24 short circuits its left hand winding at the contact of springs 95 and the relay is thereafter maintained energized by its right hand winding alone. After the conversation is completed, the connection is 90 released by the hanging up of the receiver at the calling telephone, thereby the circuit of the connector line relay 35 is opened. This opens the circuit of the relay 64 which de-energizes and closes the circuit of the release magnet 49. This circuit extends from earth 95 100

G⁶ through springs 76 and 75, 77 and 96 shaft controlled contact 97 and magnet 49 to battery B. The switch is restored to normal position immediately on the energization of the magnet 49. The relay 64, on de-energizing also opens the holding circuit of the switch C and meter relay 24. The holding circuit of the switch C² is opened by the deenergization of relay 24 and said switch

10 is permitted to restore to normal position.

In case the wanted line is already engaged, the connector does not complete connection therewith, the calling subscriber being given a busy signal in a well known manner, and 15 since the relay 36 is not energized, the calling subscriber's meter is not operated.

While a particular form of the invention has been shown herein, and the invention has been illustrated in connection with a particular type of telephone system, it is evident that it may be applicable in other forms and in other types of systems.

It is further evident that the relay 23 is not necessary if the secondary line switches 25 are controlled over the line circuit in the same manner as the primary switches are controlled, or in systems where secondary switches are not employed. In such cases the master switch contacts may be connected 30 to the holding conductor of the junction lines in known manner.

Having thus described my invention, what I claim and desire to secure by Letters Patent, is:

35 1. In a telephone system, a meter, a plurality of differential relays, and a circuit for said meter controlled by any one of said relays.

40 2. In a telephone system, a meter, a progressively movable switch associated with said meter, a plurality of differential relays, a circuit for each relay, a busy test circuit associated with each relay, said progressively movable switch controlled over said 45 test circuits to find one of said differential relay circuits to control said differential relay and to in turn control the operation of said meter.

50 3. In a telephone system, a calling line, a meter associated therewith, trunk lines, means for connecting said calling line with one of said trunk lines, and a differential relay in said trunk line for controlling the operation of said meter.

55 4. In a telephone system, calling lines, a meter associated with each of said lines, a differential relay common to said lines, means for connecting any one of said lines with said differential relay, said meters controlled by said differential relay.

60 5. In a telephone system, a calling line, a meter associated therewith, trunk lines, a differential relay and a controlling relay for each of said trunk lines, a busy test circuit

for each trunk line and means controlled 65 over said busy test circuit for extending a connection from said calling line to one of said trunk lines and for closing a circuit through said meter and said controlling relay, without operating said meter, and 70 means for energizing said differential relay to shunt said controlling relay to thereby operate said meter.

6. In a telephone system, a calling line, a measured service device associated therewith, trunk lines, means for connecting said calling line with one of said trunk lines, and a differential relay in said trunk line for controlling the operation of said measured service means. 80

7. In a telephone system, a calling line, a meter associated therewith, trunk lines, a progressively movable switch for connecting said calling line with one of said trunk lines, and a differential relay in said trunk line 85 for controlling the operation of said meter.

8. In a telephone system, a calling line, a meter associated therewith, trunk lines, means for connecting said calling line with one of said trunk lines, a differential relay 90 in said trunk line, and means controlled by said differential relay for controlling the operation of said meter.

9. In a telephone system, a calling line, a meter associated therewith, trunk lines, 95 means for connecting said calling line with one of said trunk lines, a differential relay in said trunk line for controlling the operation of said meter, means associated with said trunk line for extending a connection 100 to a progressively movable switch, and means in said switch for controlling said differential relay to in turn control the operation of said meter.

10. In a telephone system, a calling line, 105 a meter associated therewith, trunk lines, means for connecting said calling line with one of said trunk lines, a differential relay in said trunk line for controlling the operation of said meter, means associated with 110 said trunk line for extending a connection to a called telephone line, said differential relay controlled from said called line for controlling the operation of said meter.

11. In a telephone system, a calling line, 115 a meter associated therewith, trunk lines, means for connecting said calling line with one of said trunk lines, a differential relay in said trunk line for controlling the operation of said meter, means associated with 120 said trunk line for extending a connection to a called line and to thereby establish a current flow in the calling line, means controlled from said called line for reversing said current flow to the calling line, said 125 differential relay operating in response to said reversal of current to operate said meter.

12. In a telephone system, a meter, a progressively movable switch associated with said meter, a plurality of differential relays, a circuit for each relay, a busy test circuit associated with each relay, said progressively movable switch controlled over said test circuits to find one of said differential relay circuits to control said differential relay and to in turn control the operation of said meter, means associated with said relay for extending a connection to another progressively movable switch, and means in said other switch for controlling the operation of said differential relay.
13. In a telephone system, a meter, a progressively movable switch associated with said meter, a plurality of relays, a circuit for each relay, a busy test circuit associated with each relay, said progressively movable switch controlled over said test circuits to find one of said relay circuits to control said relay and to in turn control the operation of said meter, means associated with said relay for extending a connection to another progressively movable switch, and means in said other switch for controlling the operation of said relay.
14. In a telephone system, a calling line, a meter associated therewith, trunk lines, means for connecting said calling line with one of said trunk lines, a differential relay in said trunk line for controlling the operation of said meter, means in said trunk line for extending a connection to another progressively movable switch, means in said other switch for establishing a current flow in one direction in said relay without operating the same, and means for reversing said current flow to operate said relay to in turn control said meter.
15. In a telephone system, a calling line, a meter associated therewith, trunk lines, means for connecting said calling line with one of said trunk lines, a differential relay in said trunk line for controlling the operation of said meter, means for extending a connection from said trunk to a progressively movable switch and means in said switch for varying the current in said trunk line to operate said differential relay to in turn control said meter.
16. In a telephone system, a calling line, a meter associated therewith, trunk lines, means for connecting said calling line with one of said trunk lines, a differential relay in said trunk line for controlling the operation of said meter, means for extending a connection from said trunk to a progressively movable switch and a relay in said switch for varying the current in said trunk line to operate said differential relay to in turn control said meter.
17. In a telephone system, a calling line, a meter associated therewith, trunk lines, means for connecting said calling line with one of said trunk lines, a differential relay in said trunk line for controlling the operation of said meter, means for extending a connection from said trunk to a progressively movable switch controlled over said test circuits to find one of said differential relay circuits to control said differential relay and to in turn control the operation of said meter, means associated with said relay for extending a connection to another progressively movable switch, and means in said other switch for controlling the operation of said differential relay.
18. In a telephone system, a calling line, a meter associated therewith, trunk lines, means for connecting said calling line with one of said trunk lines, a differential relay in said trunk line for controlling the operation of said meter, means associated with said trunk line for extending a connection to a called line and to thereby establish a current flow in the calling line, means controlled from said called line for varying said current flow to the calling line, said differential relays operating in response to said variation of current to operate said meter.
19. In a telephone system, a calling line, a meter individual to said line, a plurality of trunk lines, a differential relay and a test circuit for each trunk, means controlled over said test circuit for extending a connection from said calling line to one of said trunk lines, means associated with said trunk line for extending the connection to a called line, said differential relay controlled from said called line to in turn control the operation of said meter.
20. In a telephone system, subscribers' lines each provided with a meter or call register, trunk lines less in number than the number of lines for use in connecting calling and called lines, means controlled over connected called lines for altering the current flow in connected calling lines, and relays for controlling the meters of connected calling lines in response to alterations of current flow therein, each relay being individual to a trunk line whereby a small number of relays is enabled to control a large number of meters.
21. In a telephone system, subscribers' lines each provided with a meter or call register, means including a trunk line for connecting any line when calling with a called line, a relay individual to said trunk line and responsive to current variations in the circuit of a connected calling line, and a meter control circuit completed during the establishment of a connection whereby the meter associated with the calling line is brought under control of said relay.
22. In a telephone system, subscribers' lines each provided with a meter or call register, means including a trunk line for connecting any line when calling with a called line, a relay individual to said trunk line for controlling the meter associated with

- a connected calling line, and a winding of said relay including a talking conductor of the trunk, whereby the relay is rendered responsive to a current variation in the calling line circuit. 5
23. In a telephone system, subscribers' lines each provided with a meter or call register, means including a trunk line for establishing a talking circuit between a calling line and a called line, a relay in said talking circuit individual to said trunk line for controlling the meter associated with a connected calling line, and a second relay connected in bridge of the connected called line for controlling said first relay. 10
24. In a telephone system, subscribers' lines each provided with a meter or call register, a trunk line, individual switches for said lines having access to said trunk line whereby a calling line may be connected thereto, means including a plurality of additional automatic switches for extending the said trunk line into connection with a called line, a circuit for operating said automatic switches and a relay individual to said trunk line included in the operating circuit of said switches for operating the meter associated with the connected calling line to register the call. 15
25. In a telephone system, subscribers' lines each provided with a meter or call register, a trunk line, individual switches for said lines having access to said trunk line whereby a calling line may be connected thereto, means including a plurality of additional automatic switches for extending the said trunk line into connection with a called line, a circuit for operating said automatic switches, a relay individual to said trunk line included in the operating circuit of said switches, and a circuit under control of said relay for operating the meter associated with the connected calling line. 20
26. In a telephone system, subscribers' lines each provided with a meter or call register, a trunk line, individual switches for said lines having access to said trunk line whereby a calling line may be connected thereto, means including a plurality of additional automatic switches for extending the said trunk line into connection with a called line, a circuit for operating said automatic switches, a relay individual to said trunk line included in the operating circuit of said switches for operating the meter associated with the connected calling line to register the call, and a second relay controlled over the connected called line for controlling said first relay. 25
27. In a telephone system, subscribers' lines each provided with a meter or call register, a trunk line, individual switches for said lines having access to said trunk line whereby a calling line may be connected thereto, means including a plurality of additional automatic switches for extending the said trunk line into connection with a called line, a circuit under control of said relay for operating the meter associated with the connected calling line circuit, and a second relay individual to said trunk line and responsive to current variations in the circuit of a connected calling line, and a meter control circuit completed during the establishment of a connection whereby the meter associated with the calling line is brought under control of said relay. 30
28. In a telephone system, subscribers' lines each provided with a meter or call register, means including a plurality of serially related automatic trunking switches for connecting a calling and a called line, an operating circuit for each switch, and a relay individual to a switch intermediate in the series and included in its operating circuit for controlling the operation of the meter on the connected calling line. 35
29. In a telephone system, subscribers' lines each provided with a meter or call register, means including a plurality of serially related trunk lines for connecting a calling and called line, a relay individual to the first trunk line of the series for controlling the operation of the meter on the connected calling line, and a second relay individual to the last trunk in the series for controlling said first relay, and means for maintaining said first relay energized independent of the second relay. 40
30. In a telephone system, subscribers' lines each provided with a meter or call register, trunk lines and automatic progressively movable switches associated therewith less in number than the number of lines for use in connecting calling and called lines, means controlled over connected called lines for altering the current flow in connected calling lines, and relays for controlling the meters of connected calling lines in response to alterations of current flow therein, each relay being individual to a trunk line whereby a small number of relays is enabled to control a large number of meters. 45
31. In a telephone system, subscribers' lines each provided with a meter or call register, means including a trunk line terminating in an automatic progressively movable switch for connecting any line when calling with a called line, a relay individual to said trunk line and responsive to current variations in the circuit of a connected calling line, and a meter control circuit completed during the establishment of a connection whereby the meter associated with the calling line is brought under control of said relay. 50
32. In a telephone system, subscribers' lines each provided with a meter or call register, means including a trunk line terminating in an automatic progressively movable switch for connecting any line when calling with a called line, a relay individual to said 55

trunk line for controlling the meter associated with a connected calling line, and a winding of said relay including a talking conductor of the trunk, whereby the relay is
5 rendered responsive to a current variation in the calling line circuit.

In testimony whereof I affix my signature in the presence of two witnesses.

ARTHUR J. RAY.
